[57] CLAIM

The ornamental design for a combined bottle and cap, as shown and described.

DESCRIPTION

FIG. 1 is a perspective view of a first embodiment of a combined bottle and cap showing our new design;

FIG. 2 is a front elevation thereof, the rear elevation being a mirror image of said front elevation;

FIG. 3 is a top view thereof;

FIG. 4 is a bottom view thereof;
FIG. 5 is a first side elevation thereof; and
FIG. 6 is a second side elevation thereof for the side opposite that shown in FIG. 5;
FIG. 7 is a perspective view of a second embodiment of a combined bottle and cap showing our new design;
FIG. 8 is a front elevation thereof, the rear elevation being a mirror image of said front elevation;
FIG. 9 is a top view thereof;
FIG. 10 is a bottom view thereof;
FIG. 11 is a first side elevation thereof; and
FIG. 12 is a second side elevation thereof for the side opposite that shown in FIG. 11;
FIG. 13 is a perspective view of a third embodiment of a combined bottle and cap showing our new design;
FIG. 14 is a front elevation thereof, the rear elevation being the same;
FIG. 15 is a top view thereof;
FIG. 16 is a bottom view thereof; and
FIG. 17 is a side elevation thereof, the opposite side elevation being the same;
FIG. 18 is a perspective view of a fourth embodiment of a combined bottle and cap showing our new design;
FIG. 19 is a front elevation thereof, the rear elevation being a mirror image of said front elevation;
FIG. 20 is a top view thereof;
FIG. 21 is a bottom view thereof;
FIG. 22 is a first side elevation thereof; and
FIG. 23 is a second side elevation thereof for the side opposite that is shown in FIG. 22;
FIG. 24 is a perspective view of a fifth embodiment of a combined bottle and cap showing our new design;
FIG. 25 is a front elevation thereof, the rear elevation being a mirror image of said front elevation;
FIG. 26 is a top view thereof;
FIG. 27 is a bottom view thereof;
FIG. 28 is a first side elevation thereof; and
FIG. 29 is a second side elevation thereof for the side opposite that shown in FIG. 28;
FIG. 30 is a perspective view of a sixth embodiment of a combined bottle and cap showing our new design;
FIG. 31 is a front elevation thereof, the rear elevation being the same;
FIG. 32 is a top view thereof;
FIG. 33 is a bottom view thereof; and
FIG. 34 is a side elevation thereof, the opposite side elevation being the same.
